METHOD AND APPARATUS FOR STABILIZING THE PRESSURE OF THE DRAWING ROLLS OF TEXTILE MACHINERY

William H. Sanders, Gastonia, N. C., assignor to Parks-Cramer Company, Fitchburg, Mass., a corporation of Massachusetts

Application October 18, 1933, Serial No. 694,181

18 Claims. (Cl. 19—137)

This invention relates to pressure stabilizing mechanism for the feed rolls or so-called draft rolls of the general type used in textile spinning machinery and preparatory machinery for drawing out and delivering continuous strands of textile fibres in the form known as roving, sliver, or yarn, and other analogous machinery.

In mechanism of this general class the material travels between the cooperating surfaces of one or more pairs of rolls or their equivalent. One roll of each pair is usually fluted and positively driven, and the other, usually the upper roll, is covered with a resilient material, such as leather or cork, and is subjected to sufficient pressure to cause the material to be grasped by the rolls with sufficient firmness to insure positive and continuous delivery of the material.

In certain other analogous mechanisms each roll in a pair may be uncovered in which case the material usually travels between the surface of one roll, usually the upper of the two, and the surface of a continuous apron composed of resilient material, such as leather, which also runs between the two rolls and beneath the material. The apron used in this case is the counterpart of a resilient roll covering in that it serves the same purpose of providing a resilient cushion for the material which protects it from injury by the pressure to which the upper roll is subject.

In all such mechanisms there is a marked tendency for chattering or vibratory motion of the upper roll to occur with consequent variation in the pressure effective between the rolls whenever the upper roll rises or falls, as it must, in response to inequalities in the material.

Such vibration is largely due to the resilient nature of the roll covering or the apron, as the case may be, coupled with such other causes as the inertia of the weights or the elasticity of springs used in the pressure applying mechanism and to sympathetic vibration due to vibration of the machine as a whole, or to vibration of the factory floor.

Such oscillation or vibratory motion of the top roll weighting mechanism is clearly observable and is generally recognized in the art as being one of the principal causes of unevenness in yarn, roving, and sliver, and of end breakage and consequent waste of material and reduced production.

I have discovered that such vibration and consequent unevenness in, or breakage of, the material may be minimized and practically eliminated and that uniformity of the quality and the quantity of product may be correspondingly im-

proved and increased by maintaining substantially uniform elastic pressure on the top rolls and retarding or dampening the movement of the top rolls when displacement occurs by reason of variations in thickness of the traveling material or by oscillations otherwise produced.

I have selected for illustrative purposes a preferred embodiment of the invention as applied to a common form of draft roll mechanism that is in wide use on cotton textile spinning machinery. In this construction the draft roll mechanism comprises a set of lower fixedly journaled fluted rolls which are positively driven at such different speeds as effect proper drawing of the material and cooperating upper draft rolls, commonly known as top rolls, covered with a resilient material to cooperate with the fluted surfaces of the respective lower draft rolls. Two or more of the successive top draft rolls are subject to pressure applied through devices known as saddles which are supported upon the top roll journals and cause the rolls to grasp the strand of material passing between them and the lower rolls with sufficient firmness to accomplish properly the process of drafting.

The saddles are subjected to pressure by means of a link known as a stirrup which is suspended on an adjustably positioned seat on the saddle and depends therefrom between adjacent pairs of top rolls and lower draft rolls, the lower end of the stirrup being connected with mechanism for applying tension to said stirrup to produce the required pressure.

The mechanism hitherto commonly used for this particular purpose comprises a lever which is seated in the lower eye of the stirrup, the longer arm of the lever being loaded with a weight at the outer end thereof, and the shorter arm of the lever being anchored by an eye-bolt to a girder extending lengthwise of the machine and known as the roller beam which girder carries longitudinally spaced upright supports known as roll stands in which the lower rolls are journaled.

In such usual type of top roll weighting mechanism it is necessary to use heavier weights than would be required for generating only the pressure essential to normal operation of the rolls in order that the additional weight may resist elevation of the rolls both by additional pressure and by the inertia of the weight as a whole, but when the rolls are returned to their normal position, after being raised by the passage of thicker material than normal, the inertia of the weight and the resilience of the top roll coverings operate

to cause objectionable vibratory motion of the saddle mechanism and corresponding variation in the pressure applied to the top rolls. Any increase in the thickness of the material passing under a top roll weighted in such manner causes the roll to rise momentarily thereby lifting the saddle and stirrup in opposition to the resistance due to the weight and to its inertia. The sudden lifting impulse thus imparted to the weight often causes it to be carried upward too far by its own inertia and thus produces, first, momentarily excessive pressure followed by a momentarily deficient pressure.

Upon the subsequent descent of the weight its inertia again causes a sudden increase in pressure that amounts to an actual blow delivered upon the top roll. The resulting impact and compression of the resilient material with which the top rolls are covered causes the weight to rebound after its sudden fall and causes further persistent vibration and variations in pressure. It thus develops that the natural variations in the material imparts sudden and violent oscillation and vibration to the various parts of the weighting mechanism and corresponding alternations of excessive and deficient pressure that tend to injure the material in process, and also to cause rapid deterioration of the top roll covering by frequent and persistent excessive shock and pressure.

Deficient pressure frequently reaches so low a value that the tension due to the winding action of the spinning mechanism causes the thin strand of untwisted material to slip through the last pair of draft rolls and thus breaks down the strand. The value and uniformity of the pressure imposed upon the top rolls are of major importance for the saddle and top rolls are subject to change in vertical position as above described in response to inequalities in the material passing beneath them and any variation in pressure due to their sudden displacement or to their vibratory motion causes uneven drafting which results in frequent injury and breakage of the attenuated material beneath them with consequent interruption of production, loss by waste, and the necessity for corresponding increased attention upon the part of the machine tenders for the piecing-up of the broken ends.

Furthermore, uniformity in pressure will increase the life of the covering of the top rolls which because of their resilient nature are particularly subject to vibration and to consequent deterioration.

The scope of my invention is, however, not limited to its use upon machines for cotton manufacturing as herein disclosed in the preferred embodiment of the invention.

Closely analogous mechanisms are widely used in other branches of the textile industry and notably in the woolen and worsted industries. In certain of these industries top draft rolls covered with resilient material are used and are subject in some cases to pressure applied by weights, and in other cases to pressure applied by springs. In certain other instances drafting mechanisms analogous to those herein described are used in which there are cooperating pairs of rolls both of which are fluted. In such cases the resilient covering of the top roll has its counterpart in a leather apron which runs between the fluted rolls and thus provides a resilient cushion for the material which passes beneath the lower surface of the upper roll and the upper surface of the apron which runs above the lower fluted roll.

In all such cases there are present the same

analogous features of a movable roll subject to pressure and to motion, a companion roll in fixedly positioned bearings, and a continuous surface of resilient material between which and the surface of the movable feed roll the material is being processed and delivered.

In all such cases vibration and chattering are the main causes of unevenness in the product and injury and breakage of the material in process, and of rapid deterioration of either the resilient roll covering or the apron as the case may be.

My invention is equally applicable to all such analogous mechanisms. The distinguishing characteristic of my invention is the provision of means for applying elastic pressure and dampening or shock absorbing means acting conjointly to maintain the cooperating rolls of a drafting mechanism of any of the classes described in non-vibratory operating engagement with the material passing therebetween.

The primary object, therefore, of the invention is to provide a textile machine having draft mechanism including a top draft roll or rolls with means for applying uniform pressure to the top roll or rolls and dampening or shock absorbing means acting in conjunction with said pressure applying means to prevent vibration of the top roll or rolls, whereby the top rolls are permitted to undergo gradual vertical displacement from and to return to their normal position in accordance with inequalities in the material in process without sudden or vibratory motion of said rolls and without substantial variation in the value of pressure applied.

A further object of the invention is to provide a mechanism of the character described having a minimum number of parts and including means attached to the structure of the machine for applying uniform elastic pressure to the saddles in a predetermined desirable direction, and also including means for dampening and retarding the necessary vertical movements of the saddles and top rolls thereby to prevent sudden or vibratory motion thereof.

Another object of the invention is to provide a mechanism including a spiral spring disposed in effective concentric alinement with the stirrup acting to subject the saddle and top rolls to elastic pressure of substantially uniform value and direction in combination with hydraulic means for controllably dampening and retarding the longitudinal movement of the stirrup, whereby the top rolls are subject only to gradual displacement from their normal position without sudden or vibratory motion.

A further object of the invention is to provide a self-contained mechanism assembled in compact form as an article of manufacture adapted to be applied to the saddle mechanism of a usual construction and comprising spring-operated means adapted to apply substantially uniform pressure to the top rolls in a predetermined direction by connection with the stirrup, and also including hydraulic dampening or shock absorbing means for retarding the motions of said spring-operated means to prevent vibratory motion thereof, or of the parts operated thereby.

An illustrative embodiment of the invention is shown in the accompanying drawings, in which,

Fig. 1 is a fragmentary front elevational view of a roll stand whose upper feed rolls are equipped with pressure mechanism constructed in accordance with the present invention;

Fig. 2 is an enlarged vertical section on line 2-2 Fig. 1;

Fig. 3 is an enlarged fragmentary vertical section on line 3—3 Fig. 1; Fig. 4 is a section on line 4—4 Fig. 3 viewed downwardly.

5 A preferred embodiment of the invention is illustrated in the drawings as applied to a cotton spinning machine of a usual type in which hydraulically controlled spring pressure mechanism has been substituted for the weighted arm mechanism commonly employed in machines of 10 this type.

15 Referring in detail to the drawings, the machine frame or bed 5 carries a roller stand 6 which is provided with a plurality of series of lower feed rolls 7 and upper feed rolls 8. A saddle 9 is shown resting upon two of the upper feed rolls of each series or set as is common in the art, but it will be understood that a pair of 20 overlapping saddles may be employed as is also common in the art when it is desired to maintain pressure upon all of the upper feed rolls of each series or set.

25 The preferred embodiment of the invention shown in the accompanying drawings comprises a combined spring tension device and a hydraulic dampening or shock absorbing mechanism consisting of a cylinder with a piston reciprocable therein adapted to be connected to the movable rolls or the saddles for such rolls, with a spring interposed between the piston and the adjustable upper end of the cylinder. Suitable means are provided to permit a restricted flow of the fluid from one side of the piston to the other thereby 30 to resist the movement of the piston in either direction so that the spring and dampening device act conjointly to maintain a predetermined substantially uniform pressure upon the movable feed rolls and to minimize and effectively prevent vibration thereof. As shown, this combined device includes a cylinder 10 rigid with a 35 forwardly and downwardly extending standard 11 having a wide flat base 12 resting flatly upon the upper surface of the machine frame or bed 5 and rigidly secured to the latter by means of a bolt 13 passing through an opening in the machine frame or bed 5 and threaded into an axial bore or socket provided in the lower end of the standard 11, said opening in the machine frame or bed 5 being the one ordinarily provided to 40 receive the stem of an eye bolt by which the weighted lever of the ordinary pressure mechanism is usually pivotally anchored to the machine frame. It will be noted by this means the cylinder 10 is supported at an inclination so as to be axially aligned with the associated stirrup 14 when in use, whereby a true straight line pull will be exerted upon said saddle link as and by 45 means to be presently described, thereby placing the upper feed rolls under a uniform even pressure at all times. Loosely and slidably fitted in the cylinder 10 is a piston 15 which works in a body of viscous fluid, such as oil, 16 that is placed within the cylinder 10. The loose fitting 50 of the piston 15 within the cylinder 10 provides for restricted passage of the oil or other fluid past said piston, so that movement of the latter will be damped and retarded in a manner generally similar to dash pot or shock absorbing 55 constructions of the hydraulic type.

60 The terms "dampening" and "shock-absorbing" are herein used to specifically describe the absorption and final dissipation of kinetic energy by the application of resistance in opposition to motion. The aforesaid terms are herein used in

6 specific contra-distinction to the cushioning action of springs, which, when used in opposition to motion, merely accumulate potential energy by their distortion, which is subsequently delivered as kinetic energy by the recoil of the 10 spring. It is to be especially observed that such cushioning action not only fails to prevent or minimize vibration but often tends, on the contrary, to promote and to amplify and prolong vibration, while the dampening or shock-absorbing 15 action that is an outstanding characteristic of the means employed for the purposes of my invention effectively minimizes or prevents vibratory motion.

20 Again, it is to be particularly noted that the dampening means employed for the purpose of my invention are strictly non-elastic and serve a novel and entirely different purpose from the elastic means such as springs of various types which are so commonly used in the art for "cushioning" and which because of their elastic nature are incapable of producing true dampening, as hereinbefore explained.

25 The effective dampening of roller and saddle motion as accomplished by my invention and the non-elastic means employed to effect such dampening are therefore outstanding and distinguishing characteristics of my invention. This provides for slow even movement of the piston in either direction and obviates sudden movement 30 thereof in opposition to vibration or the like, for a purpose which will presently become apparent. Threaded into the upper end of cylinder 10 for adjustment longitudinally of the latter is a head 35 17 having a central opening through which slidably projects a rod 18 rigid with and extending upwardly from the piston 15, the upper projecting end of rod 18 being formed as at 19 for connection with the lower end of stirrup 14. Surrounding the rod 18 within the cylinder 10 and 40 between the piston 15 and plug 17 is a compression spring 20 by which a downward pull is exerted upon the rod 18 and stirrup 14 in a straight line to subject the upper feed rolls 8 to a uniform 45 pressure which may be varied to suit requirements by adjustment of head 17 longitudinally of cylinder 10 so as to vary the normal tension of spring 20 when the device is in use. The use of a spring tension device alone or in angular 50 relation to the stirrup 14 is open to the objection that the same would not provide for a straight line pull upon the saddle link and would not successfully oppose sudden movement thereof due to a sudden jerk or vibration, and the result would be lack of uniform pressure attendant with 55 frequent end breakage and the production of threads which would vary considerably in thickness. I overcome these objections by supporting the cylinder 10 at an inclination so that the piston rod 18 is in direct line with the saddle link 14, 60 and by providing the rod 18 with a piston 15 operating in the thick fluid 16 so that the action of the spring 20 is retarded. In other words, sudden expansion and compression of spring 20 is opposed by this hydraulic dampening or shock absorbing means so as to effectively prevent sudden 65 movement or vibration of rod 18 and saddle link 14. Obviously, downward movement of rod 18 is controlled and retarded by compression of the fluid 16 beneath the piston 15, and due to the 70 fact that such fluid is restricted in its upward passage past the piston 15 at such time. In a like manner, upward movement of rod 18 and saddle link 14 is controlled and retarded because the corresponding upward movement of piston 75

15 produces a partial vacuum therebeneath which is slowly relieved by the downward passage of the fluid past the piston 15. It will thus be seen that I not only have overcome the objections of the ordinary weighted lever pressure mechanism by the use of a spring device in which the pull exerted upon the stirrup is always in the same direction, but I prevent sudden movement or vibration of the movable parts of such 10 spring device by a hydraulic dampening means, whereby the uniform pressure maintained by the spring upon the upper rolls is effectively insured without permitting excessive vibration and the like. I have found that in actual practice and as a result of extended use, the present pressure mechanism enables the production of threads of substantially uniform thickness, and practically eliminates the occurrence of end breakage.

20 The mechanism for applying pressure to and for dampening the vibration of the top rolls of drawing mechanism above described is of a simple character and may be conveniently constructed as an article of manufacture adapted to be substituted for the pressure applying means 25 of spinning machines and analogous machines of the prior art without modification or substantial change in the construction of such machines. It, of course, may be readily incorporated in new 30 machines without substantial modification of the saddle mechanism or other structure of the machine.

35 While I have illustrated the pressure applying means and the mechanism for minimizing and practically eliminating vibration of the top roll mechanism as a unit construction, similar operating hydraulic mechanism or its equivalent may be independently applied to the usual type of lever and weight mechanism, or to usual types of 40 spring pressure applying mechanism, and various changes in form, construction and arrangement of parts may also be made within the scope of my invention.

45 It will, therefore, be understood that the particular embodiment of the invention shown and described herein is of an illustrative character and is not restrictive of the meaning and scope of the claims.

What I claim as new is:

50 1. A textile machine having means for continuously drafting a moving strand composed of textile fibres comprising cooperating relatively movable drawing members, yieldable means acting upon said drawing members to apply pressure to the material being drawn therebetween, and non-elastic dampening means cooperating with 55 said pressure-applying means to resist sudden movement of said movable members and dissipate energy expended in overcoming said resistance.

60 2. A textile machine having means for continuously drafting a moving strand composed of textile fibres comprising cooperating relatively movable drawing members, yieldable means acting upon said drawing members to apply pressure to the material being drawn therebetween, and non-elastic means acting conjointly with 65 said pressure applying means to dampen sudden or vibratory movements thereof, thereby to stabilize the pressure effective upon the material.

70 3. A textile machine having means for continuously drafting a moving strand composed of textile fibres comprising cooperating relatively movable drawing members, yieldable means acting upon said drawing members to apply pressure 75 to the material being drawn therebetween,

and hydraulic means associated with said yieldable pressure applying means and acting conjointly therewith to retard and dampen sudden or vibratory movements of said relatively movable drawing members, thereby to stabilize the pressure effective upon the material.

4. A textile machine having means for continuously drafting a moving strand composed of textile fibres having cooperating lower and top drawing rolls, yieldable means acting upon said top rolls to apply pressure to the material being drawn between said rolls, and non-elastic dampening means acting conjointly with said pressure applying means to minimize oscillatory movements of said top roll by retardation of sudden 15 and vibratory movements thereof, thereby to stabilize the pressure effective upon the material.

5. A textile machine having mechanism for continuously drafting a moving strand composed of textile fibres comprising a set of fixedly journaled rolls, a set of relatively movable rolls cooperating therewith, a saddle for said movable rolls, yieldable means for applying pressure to said saddle, and dampening means operable to apply non-elastic resistance to any sudden motion of said movable rolls and acting conjointly with said pressure-applying means to subject said material to substantially uniform pressure by preventing vibratory motion of said movable rolls.

30 6. A textile machine having means for continuously drafting a moving strand composed of textile fibres having a set of fixedly journaled lower draft rolls, a set of cooperating top draft rolls, a saddle mechanism supported on the journals of said top rolls, a stirrup suspended from a seat on said saddle, means for applying tension to said stirrup including a spring acting downwardly upon said stirrup in axial alignment therewith, and hydraulic means associated with said pressure applying means and acting conjointly therewith to dampen sudden or vibratory movements of said top rolls, thereby to stabilize the pressure effective upon the material.

45 7. A textile machine having means for continuously drafting a moving strand composed of textile fibres having a set of fixedly journaled lower draft rolls, a set of cooperating top draft rolls, a saddle mechanism supported on the journals of said top rolls, a stirrup suspended from a seat 50 on said saddle, means for applying tension to said stirrup including a spring acting downwardly upon said stirrup in axial alignment therewith, and hydraulic dampening means also acting upon said stirrup in axial alignment therewith and 55 conjointly with said spring to restrict the amplitude of movement of said top rolls and to prevent sudden and vibratory movements thereof, thereby to stabilize the pressure effective upon the material.

60 8. In a device of the character described, in combination, a roll stand bed, a roll stand mounted upon said bed, feed rolls in said roll stand, a saddle bearing on certain of said feed rolls, a stirrup connected with said saddle and extending between said feed rolls toward said roll stand bed, a hydraulic dampening device, means mounting the same upon said roll stand bed in an inclined position longitudinally aligned with said stirrup, said dampening device having a piston provided with an axial upwardly projecting rod connected to said stirrup, and a spring exerting a downward pull upon said stirrup.

70 9. In a device of the character described, in combination, a roll stand bed, a roll stand mounted 75

- upon said bed, feed rolls in said roll stand, a saddle bearing on certain of said feed rolls, a stirrup connected with said saddle and extending between said feed rolls toward said roll stand 5 bed a hydraulic dampening device, means mounting said dampening device upon said roll stand bed in an inclined position longitudinally aligned with said stirrup, said dampening device having a piston provided with an axial upwardly projecting rod connected to said stirrup, and a spring exerting a downward pull upon said stirrup, said dampening device further including a cylinder having an axially adjustable head in the upper end thereof through which said piston 10 rod slidably extends, and said spring being of the compression type and encircling said rod within said cylinder, between said head and said piston, whereby the tension of said spring may be adjusted by longitudinal adjustment of the head 15 relatively to said cylinder.
10. A textile machine of the character described having drafting roll mechanism comprising a set of lower draft rolls, a set of top draft rolls resting thereupon in operative engagement, 20 a saddle bearing upon the journals of said top rolls, a stirrup positioned at its upper end in an adjustable seat on said saddle, a fixture positioned below said rolls comprising a hollow cylinder disposed beneath said saddle in axial alignment with said stirrup seat, a piston movable lengthwise within said cylinder having a piston rod connected with said stirrup in axial alignment therewith, an apertured head adjustably positioned in said cylinder and surrounding said 25 rod, a spiral spring disposed in compression between said head and said piston, and a body of viscous liquid filling the lower portion of said cylinder to above said piston acting conjointly with said spring to maintain uniform elastic pressure upon said saddle and top rolls and to retard the movements of said piston and thereby to minimize the vibration of said saddle and top rolls.
11. As an article of manufacture, a device for applying elastic pressure to the top rolls of the drafting mechanism of a textile machine and to dampen the vibratory movement thereof comprising a cylinder closed at its lower end and having an apertured head at the opposite end, 30 a piston movable lengthwise within said cylinder having a piston rod extending through said said aperture and provided at the outer end thereof with means for operative connection to the top rolls of said machine, means for securing said cylinder to the frame of the machine, a spiral spring disposed within said cylinder for compression between said piston and said head, and a body of liquid filling the lower portion of said cylinder to above said piston.
- 50 12. As an article of manufacture, a device for applying yielding pressure through a saddle and stirrup to the top rolls of the drafting mechanism of a textile machine, comprising relatively movable members adapted to be attached respectively to a rigid part of the machine and to the top roll stirrup, a spring of predetermined strength intermediate of said relatively movable members, and supplemental dampening means operable to apply non-elastic resistance to the 55 relative movement of said movable members in response to displacement of said top rolls and acting conjointly with said spring to maintain substantially uniform pressure on said top rolls by preventing vibration thereof.
- 70 13. As an article of manufacture, a device for applying yielding pressure through a saddle and stirrup to the top rolls of the drafting mechanism of a textile machine, comprising relatively movable members one of which is adapted to be anchored to a stationary part of the machine and the other of which is adapted to be detachably connected to the top roll stirrup, a spring of predetermined strength intermediate of said relatively movable members, means for varying the initial force applied by said spring to said stirrup, and supplemental dampening means operable to apply non-elastic resistance to the relative movements of said members and cooperating with said spring to stabilize the pressure applied to said top rolls and prevent vibratory motion thereof.
14. As an article of manufacture, a device for applying yielding pressure through a saddle and stirrup to the top rolls of the drafting mechanism of a textile machine, comprising relatively movable members adapted to be attached respectively to a rigid part of the machine and to the top roll stirrup, a spring of predetermined strength disposed to react upon said relatively movable members, and hydraulic dampening means also interposed between said relatively movable members acting conjointly with said spring to restrict the relative movements of said members, and thereby to stabilize the pressure applied to said top rolls.
15. As an article of manufacture, a device for applying yielding pressure through a saddle and stirrup to the top rolls of the drafting mechanism of a textile machine, comprising a cylinder closed at its lower end and having means for attachment to the frame of the machine, an apertured head closing the other end of said cylinder, a piston reciprocable in said cylinder operable to resist the passage of surrounding liquid upon reciprocation of the piston and having a piston rod extending through said head and provided with means detachably to engage the top roll stirrup, a compression spring of predetermined strength interposed between said piston and said head, and a body of liquid filling said cylinder to above said piston and acting upon reciprocation of the piston to restrict the amplitude of movement of the top rolls, thereby to prevent vibration thereof.
16. As an article of manufacture, a device for applying yielding pressure through a saddle and stirrup to the top rolls of the drafting mechanism of a textile machine, comprising a cylinder closed at its lower end and having means for attachment to the frame of the machine, an apertured head adjustably mounted upon the other end of said cylinder, a piston reciprocable in said cylinder operable to restrict the passage of surrounding liquid upon reciprocation of the piston and having a piston rod extending through said head provided with means detachably to engage the top roll stirrup, a compression spring of predetermined strength interposed between said piston and said head, and a body of liquid filling said cylinder to above said piston acting upon reciprocation of the piston to restrict the amplitude of vibration of the top rolls thereby to dampen the vibration thereof, and means whereby the position of said cylinder head may be adjusted to determine the value of the force exerted by said spring upon said stirrup.
17. As an article of manufacture, a device for applying pressure through a saddle and stirrup to the top rolls of the drafting mechanism of a textile machine, comprising a cylinder closed at its lower end and having means for attachment to the frame of the machine, an apertured head adjustably mounted upon the other end of said cylinder, a piston reciprocable in said cylinder operable to restrict the passage of surrounding liquid upon reciprocation of the piston and having a piston rod extending through said head provided with means detachably to engage the top roll stirrup, a compression spring of predetermined strength interposed between said piston and said head, and a body of liquid filling said cylinder to above said piston acting upon reciprocation of the piston to restrict the amplitude of vibration of the top rolls thereby to dampen the vibration thereof, and means whereby the position of said cylinder head may be adjusted to determine the value of the force exerted by said spring upon said stirrup.

tile machine, comprising a cylinder closed at its lower end and having means for attachment to the frame of the machine, an apertured head closing the other end of said cylinder, a piston reciprocable in said cylinder having a predetermined clearance relative to the cylinder bore and having a piston rod extending through said head provided with means detachably to engage the top roll stirrup, a compression spring of predetermined strength interposed between said piston and said head, and a body of suitable liquid filling said cylinder to above said piston operable upon reciprocation of the piston to restrict the amplitude of movement of the top rolls and thereby to dampen vibration thereof.

18. As an article of manufacture, a device for applying yielding pressure through a saddle and stirrup to the top rolls of the drafting mechanism of a textile machine, comprising a cylinder closed at its lower end and having means for at-

5 tachment to the frame of the machine, an apertured head constituting the upper end of said cylinder, a piston reciprocable within said cylinder operable to restrict the passage thereby of surrounding liquid upon reciprocation of the piston, said piston having a piston rod extending through said apertured head and adapted for non-rigid connection to said stirrup in organization 10 acting to maintain mutual self-alinement of said cylinder, piston and stirrup, a compression spring of predetermined strength interposed between said piston and said cylinder head, and a body of suitable liquid filling said cylinder to above said piston acting upon reciprocating movements of 15 the piston to resist displacement of the top rolls and thereby to prevent vibration thereof by the dampening action of said fluid upon the movements of said piston.

WILLIAM H. SANDERS. 20
